T. T. TVEDT.

MUFFLER.

APPLICATION FILED SEPT. 12, 1917.

1,345,418.

Patented July 6, 1920.

UNITED STATES PATENT OFFICE.

THOMAS T. TVEDT, OF BROOKLYN, NEW YORK.

MUFFLER.

1,345,418.

Specification of Letters Patent.

Patented July 6, 1920.

Application filed September 12, 1917. Serial No. 190,955.

To all whom it may concern:

Be it known that I, THOMAS T. TVEDT, a citizen of the United States, residing at Brooklyn, New York, have invented certain 5 new and useful Improvements in Mufflers, of which the following is a clear, full, and exact description.

This invention relates to sound muffling or silencing devices, and particularly to 10 mufflers adapted to silence the exhaust from internal combustion engines.

A general object of the invention is to provide a muffler with which a maximum of silencing effect may be produced with 15 a minimum of back pressure upon the engine.

More particularly the invention aims to provide a muffler which may be adjusted to the performance of any particular engine 20 of the type for which it is designed and which, nevertheless, is simple and durable in construction and inexpensive to manufacture.

Another object of the invention is to 25 improve mufflers of the type disclosed in my co-pending application, Serial No. 152,928, filed March 6, 1917, and particularly to facilitate the expansion of the gases into the successive chambers of a muffler of 30 this type, and also to accelerate the travel of the gases through the muffler, thus further improving mufflers of this type with respect to the back pressure action upon the engine.

35 Other objects and important features of the invention will appear from the following description and claims when considered in connection with the accompanying drawings, in which—

40 Figure 1 is a longitudinal section through a muffler embodying the present invention, on the line 1—1 of Fig. 2;

Fig. 2 is a transverse section illustrating the construction of the by-pass and its close- 45 sure in the transverse baffle plate;

Fig. 3 is an end view of the outlet end of the baffle casing;

Fig. 4 is an end view of the inlet end of the baffle casing; and

50 Fig. 5 is a plan detail of the deflector by which whirling motion is imparted to the exhaust gases.

The illustrated muffler, which is of the general type of that shown in my co-pending application, Serial No. 152,928 hereinabove identified, comprises a casing formed

of end plates 2 and 4 provided in their opposed faces with annular seats 6 and 8 for the cylindrical shell 10 which forms the cylindrical outer wall of the casing, these 60 seats being somewhat beveled to insure a substantially gas-tight joint when the plates 2 and 4 are crowded toward each other and into engagement with the ends of the shell 10 by means of the connecting bolts 12, 65 which preferably have a head 14 at one end and a nut 16 threaded upon the other end. Two of the bolts 12 are arranged to constitute guides for the transverse baffle plate 18, having perforated ears 20 which receive 70 said guides. The plate 18 forms the end wall of a cylindrical baffle, the illustrated cylinder being formed by a cylindrical shell 21 seated at one end upon a flange 22 upon the plate 18, and at its other end upon a 75 flange 24 upon a ring 26 having ears 28 guided upon the rods 12, upon which the plate 18 is also guided.

The exhaust gases to be muffled are introduced into the muffler through an opening 80 30 in the wall 2 of the casing and this opening is surrounded by a cylindrical baffle comprising a cylindrical shell 32 seated upon a flange 34 upon the inner side of said plate 2, said cylinder 32 preferably ex- 85 tending within the cylinder 21, which is preferably adjustable toward and away from the open end of the cylinder 32 in the manner hereinafter to be described.

The chamber within the cylinder 32 con- 90 stitutes the first expansion chamber of the muffler, and in order to facilitate the expansion of the gases within this chamber and also within the succeeding chambers, means is preferably provided for imparting 95 a whirling motion to the gases about the common axis of the various cylinders. The illustrated means comprises a plate 36 having flanges 37 by which it is attached to the end wall 2 of the muffler casing, the plate 36 being so located that it substantially divides the opening 30, through which the exhaust gases enter the casing, upon a diameter of said opening, the plate being cut back, as shown, away from said opening so as not to 100 interfere with the free entrance of the gases into the chamber in the cylinder 32. At its end remote from the opening 30, the plate 36 is split as shown at 38, and the two parts of the plate are so bent, with respect to the 105 axis of the cylinder, as shown in Fig. 1 of the drawings, that they tend to impart a

whirling motion to the gases passing over said plate, this whirling motion being about the axis of the cylinder. Such whirling motion tends of course to effect a centrifugal movement of the gases and thus to facilitate their expansion toward the wall of the chamber, and accordingly their rapid expansion into the chamber in the succeeding cylinder 21, thereby also accelerating their travel through the muffler.

As in the muffler shown in my co-pending application hereinabove identified, the cylindrical baffles are preferably arranged for telescopic adjustment to vary the relative capacities of the succeeding expansion chambers, and in the illustrated construction means is provided for moving the cylinder 21 upon its guides 12 to carry its end wall 18 toward and away from the open end 20 of the cylinder 32. The illustrated means comprises a rod 39 threaded through the plate 18 and having a bearing in the end plate 4 of the muffler casing, this rod preferably having a squared end by which it may be engaged for turning, and having a set nut 40 by which it may be locked in adjusted position.

The illustrated muffler, like that in my co-pending application above identified, is preferably also provided with a by-pass through which, if desired, a selected proportion of the exhaust gases may be directly conducted from the first expansion chamber to the last without passing the cylindrical baffle 21. This by-pass comprises a series of ports 41 in the plate 18 within the cylinder 21, normally closed by a shutter 42 having a corresponding series of openings adapted to register with the ports 41 when the shutter is turned part way about its axis, this shutter being mounted upon a shaft 44 having a bearing in the plate 18 and a sliding bearing in the plate 4. A handle 46 upon the shaft 44 may be swung from one position to the other, as shown in Fig. 3 of the drawings, to effect the opening and closing of the ports 41.

When the muffler is used for muffling the exhausts of marine engines, means is preferably provided for cooling the muffler, the illustrated means comprising a spray pipe 48 connected with the water inlet opening 50, this spray pipe being located between the cylinder 32 and the cylindrical wall 10 of the muffler casing in such position that it sprays water over the outside of the cylinder 32. A branch 52 from the pipe 48 is preferably arranged to conduct a portion of the entering water through the wall of the cylinder 32 into the inside of the cylinder, in such position that it discharges a part of the water upon the plate 36 by which the whirling motion is imparted to the entering gases. This water not only tends to cool the muffler proper but also to cool

the gases, thus further helping to reduce the back pressure upon the engine. Both the water and the gases are conducted out of the muffler through the opening 54 in the end wall 4 of the muffler casing.

70

What I claim as new is—

1. In a muffler, a cylindrical expansion chamber open at one end, means for conducting the exhaust gases into the other end of said chamber, stationary means for imparting a whirling motion to said gases as they enter said chamber, a second expansion chamber into which said first chamber discharges from its open end, and means accessible from outside of the muffler for effecting a variation in the relative capacities of said chambers.

75

2. In a muffler, a cylindrical expansion chamber open at one end, means for conducting the exhaust gases into the other end of said chamber, means for imparting a whirling motion to said gases as they enter said chamber, a casing providing an expansion chamber outside said cylindrical chamber, a baffle plate in said casing and means accessible from the outside of the muffler for adjusting said baffle plate toward and away from the open end of said chamber.

80

3. In a muffler, a cylindrical baffle open at one end and providing an expansion chamber within, means for introducing exhaust gases into the other end, means for imparting a whirling motion to the gases as they enter the expansion chamber within said baffle, a casing outside said baffle providing a second expansion chamber, and means for conducting cooling water over the outside of said baffle and for introducing cooling water into the chamber within said baffle.

85

4. A muffler comprising a series of communicating expansion chambers, means for varying the relative capacities of said chambers, means for conducting the exhaust gases to the initial expansion chamber, and means for conducting at will a fractional portion of the gases directly from the initial chamber to the last of said series of expansion chambers.

90

5. A muffler comprising overlapping concentric cylinders of different diameters having end walls at their remote ends, said cylinders being arranged to telescope to vary the relative capacity of the successive expansion chambers, means for conducting the gases from the exhaust into said cylinders, and a valve controlled port in the end wall of one of the cylinders arranged to permit the passage of a fractional portion of the gases directly through said cylinders.

95

6. A muffler comprising a casing having therein a series of baffles forming in said casing a series of communicating expansion chambers, said baffles being relatively adjustable to vary the relative capacities of the expansion chambers, and a valve controlled

100

110

by-pass for conducting a portion of the exhaust gases past said baffles.

7. A muffler comprising overlapping concentric cylinders of different diameters having end walls at their remote ends, said cylinders being arranged to telescope to vary the relative capacity of the successive expansion chambers, means for conducting the gases from the exhaust into said cylinders, 5 and a valve controlled port in the end wall of one of the cylinders arranged to permit the passage of a portion of the gases directly through said cylinders.

8. In a muffler the combination with a muffler casing, of concentric cylindrical 15 bafflers within said casing providing successive expansion chambers for the exhaust gases, means for introducing the exhaust gases into the chamber in the innermost baffle and stationary means for imparting a 20 whirling motion to the gases on entering said innermost baffle to throw said gases toward the walls of said chamber.

Signed at New York, N. Y., this 31st day of August, 1917.

THOMAS T. TVEDT.
